P. D. GERHART

LID REMOVER

Original Filed Nov 19, 1921

Paul D. Gerhart
INVENTOR
BY Victor J. Evans
ATTORNEY

UNITED STATES PATENT OFFICE.

PAUL D. GERHART, OF EXETER, CALIFORNIA.

LID REMOVER.

Substitute for application Serial No. 516,393, filed November 19, 1921. This application filed November 28, 1924. Serial No. 752,771.

To all whom it may concern:

Be it known that I, PAUL D. GERHART, a citizen of the United States, residing at route No. 1, Box 94^A, Exeter, in the county ⁵⁵ of Tulare and State of California, have invented new and useful Improvements in Lid Removers, of which the following is a specification.

This invention relates to a lid remover ¹⁰ and is a substitution for my abandoned application which was filed November 19, 1921, Serial No. 516,398 and allowed July 28, 1922, and has for its primary object the provision of a remover that may be readily mounted ¹⁵ upon a jar or other receptacle and when in place will exert great pressure under the lid for prying the same from the jar.

An object of the invention is the provision ²⁰ of a lifter or remover that will effectively remove a well-known lid from a jar without in any way subjecting the operator to any great exertion or hazard.

A feature of the invention is the novel ²⁵ manner of constructing and arranging the parts so that a leverage action may be produced for exerting great pressure under the lid and so remove the same with the least exertion possible.

It will be noted the parts are so constructed and associated that the lifter may ³⁰ be quickly connected to or disconnected from a jar or other receptacle.

With these and other objects in view the ³⁵ invention will be better understood from the following detailed description taken in connection with the accompanying drawing wherein:

Fig. 1 is a side elevation of the remover in applied position,

Fig. 2 is a top plan view, and

Fig. 3 is a detail sectional view on the line 3—3 of Fig. 2.

Again referring to the drawing illustrating one of the many constructions of ⁴⁵ my invention, the letter B designates a jar upon which is mounted a well-known lid C that is provided with a flange D.

The numeral 1 designates the split band of my improved lifter. The ends of the ⁵⁰ band are curved outwardly to form cam

surfaces 2 for facilitating the snapping of the band around the neck of the jar and also to facilitate the removal of the band from the jar by exerting pressure upon the bent ends. The band 1 is formed with a folded portion to provide a projection 3 and further provided with supporting wings 4 that extend laterally from the projection in the opposite direction and rest upon the shoulder E. A lever 5 is pivotally connected to the projection as shown at 6 and is provided with a tooth 7 so disposed that in the swinging movement of the lever same will move into engagement with the under surface of the flange D and further movement of the lever will exert pressure great enough to force the lid from the jar. ⁶⁰ ⁶⁵

From the foregoing description taken in connection with the accompanying drawing, it will be seen that I provide a structure that ⁷⁰ may be very quickly connected and disconnected from a jar or other receptacle and which is capable of exerting great pressure at the proper point to force the cap or lid from the jar. It will also be noted that this ⁷⁵ action takes place in a manner that danger to the operator is eliminated and beside the amount of exertion necessary is reduced to a minimum.

It is, of course, to be understood that the ⁸⁰ invention may be constructed in various other manners and the parts associated in different relations and, therefore, I do not desire to be limited in any manner except as set forth in the claim hereunto appended. ⁸⁵

Having thus described my invention, what I claim is:

A lid remover comprising a split band for engagement around a jar neck, said band being formed with a folded portion to provide a projection extending at right angles to the band, wings at the lower end of the projection and extending in opposite directions for bearing on the shoulder of the jar and a lever pivoted to the projection to swing vertically and a tooth on the inner end of the lever for engagement under the jar cap. ⁹⁰ ⁹⁵

In testimony whereof I affix my signature,

PAUL D. GERHART,
